US00D942504S

(12) **United States Design Patent** (10) **Patent No.:** **US D942,504 S**
(45) **Date of Patent:** **** Feb. 1, 2022**

(54) **DISPLAY SCREEN OR PORTION THEREOF
WITH GRAPHICAL USER INTERFACE**

(71) Applicant: **Apple Inc.**, Cupertino, CA (US)

(72) Inventors: **Jody Akana**, San Francisco, CA (US);
Imran Chaudhri, San Francisco, CA (US); **Jonathan P. Ive**, San Francisco, CA (US); **Chanaka Karunamuni**, San Jose, CA (US)

(73) Assignee: **Apple Inc.**, Cupertino, CA (US)

(**) Term: **15 Years**

(21) Appl. No.: **29/745,860**

(22) Filed: **Aug. 10, 2020**

Related U.S. Application Data

(63) Continuation of application No. 29/725,252, filed on Feb. 24, 2020, now Pat. No. Des. 892,861, which is a continuation of application No. 29/672,880, filed on Dec. 10, 2018, now Pat. No. Des. 876,484, which is a continuation of application No. 29/566,152, filed on May 27, 2016, now Pat. No. Des. 835,627, which is a continuation of application No. 29/457,327, filed on Jun. 9, 2013, now Pat. No. Des. 757,798.

CLAIM

The ornamental design for a display screen or portion thereof with graphical user interface, as shown and described.

DESCRIPTION

The FIGURE is a front view of a display screen or portion thereof with graphical user interface showing the claimed design.

The broken lines in the FIGURE show a display screen or portion thereof, and form no part of the claimed design.

1 Claim, 1 Drawing Sheet
